(57) **ABSTRACT**

A wearable lower body garment for efficiently attaching and removing athletic padding, or in the alternative for enabling continuous wear of athletic padding. The lower body garment is made of durable and flexible material to allow a user freedom of movement. The lower body garment is worn as a pant-like garment that includes both flexible and adjustable straps to conform to a user's shape. The lower body garment has anchor points disposed on the outer leg portion and on the inseam that allow for attachment of athletic padding.

FIG.3

LEG GUARD MOUNT GARMENT

BACKGROUND OF THE INVENTION

The present invention relates to athletic padding and, more particularly, to a leg guard mount garment.

Traditionally, catchers in both baseball and softball wear protective padding to cover aspects of their bodies, which include: a helmet with faceguard, chest protector, and shin/knee guards. The helmet and chest protector require very little time to put on, but the shin/knee guards require a significant amount of time. Shin guards may even involve help from additional people (e.g., players, coaches and/or adults) to secure them on the catcher. The delays associated with putting on shin/knee guards can delay a pitcher's warmup. These inefficiencies are exacerbated when the catcher needs to gear-up between innings, after being the last out at-bat, or being left on-base when the last out of an inning is made. As can be seen, there is a need for a wearable garment that lessens the resources required for putting on shin/knee guards and also speed up the pace of game/playing time.

SUMMARY OF THE INVENTION

In one aspect of the present invention, a lower body garment for efficiently attaching/removing padding is disclosed. The lower body garment includes an attachment structure with a belt and a buckle, wherein the belt is adapted to suspend the attachment from the waist of a user. A plurality of outer garment straps and inner garment straps are sewn, or otherwise affixed at a proximal end to the belt. When worn the outer garment straps extend along the outer aspect of each of the user's legs, whereas the inner garment straps extend along each inseam of the user's legs. Each inner and outer strap includes a plurality of openings/holes spaced along the length of the strap whereby a leg guard/pad can be attached or removed to the holes. A plurality of adjustable straps are attached, or sewn, on one side between a pair of inner and outer garment straps. Each inner and outer garment strap pair also includes at least one flexible strap that is affixed, or sewn, on both sides. Finally, a plurality of leg pads is removably securable to the attachment structure.

These and other features, aspects, and advantages of the present invention will become better understood with reference to the following drawings, description, and claims.

BRIEF DESCRIPTION OF THE DRAWINGS

FIG. 1 is a perspective view of a leg guard attachment garment according to an embodiment of the present invention, shown in use;

FIG. 2 is an exploded view thereof; and

FIG. 3 is a sectional view thereof, taken along line 3-3 in FIG. 1.

DETAILED DESCRIPTION OF THE INVENTION

The following detailed description is of the best currently contemplated modes of carrying out exemplary embodiments of the invention. The description is not to be taken in a limiting sense but is made merely for the purpose of illustrating the general principles of the invention, since the scope of the invention is best defined by the appended claims.

Broadly, one embodiment of the present invention is a lower body garment that allows for quick and efficient attachment and removal of shin and/or leg guards, or in the alternative provides comfort such that a user can wear shin guards continuously during a game without the need to remove them. The garment bears similarities to chaps.

Referring to FIGS. 1-3, FIG. 1 illustrates a perspective view of the inventive lower body garment 100 worn by a user 30, with leg guards 200 or pads attached. A user 30 can 10 secure the garment 100 to their waist by clamping buckle 12 attached to belt 10, notably the belt can be worn circumferentially around the user's 30 waist. The garment 100 comprises outer attachment straps 14 and inner attachment straps 16. The attachment or foundation straps 14, 16 may be 15 provided in a pair for each of the user's legs, such that the outer attachment straps 14 are adapted to be worn vertically along the outer aspect of a user's 30 leg, whereas the inner attachment straps 16 are adapted to be worn vertically along the user's 30 inseam. In a preferred embodiment, a plurality 20 of outer holes 18 can be disposed along the outer attachment straps 14, and a plurality of inner holes 20 can be disposed along the inner attachment straps 16. The garment 100 can be secured to user's 30 legs by an elastic strap, which can be affixed to the outer attachment strap 14 and the inner 25 attachment strap 16 and adapted to be worn across the front of the user's 30 thigh alone or in conjunction with adjustable straps 22 which can be installed horizontally on the strap pair 14, 16, wherein each strap 22 can be worn across the back of a user's 30 thigh, a back of the user's 30 calf, or a 30 back of the user's 30 lower leg proximate to the ankle. The pads 200 may have clips 24 which can be used to removably attach the pads 200 to the garment 100 via holes 18, 20. In some embodiments, the straps 22 may be fixable and secured to the outer attachment strap 14 and removably fastened to the inner attachment strap 16 on each leg.

FIG. 2 illustrates an exploded view of inventive lower body garment. FIG. 2 illustrates the elements in FIG. 1 with the following additional details. The clasping mechanism 12 of the belt 10 is shown in further detail, however, it is 40 envisioned that any known mechanism for securing a belt 12 is contemplated by the current invention, such as a buckle. The pads 200 can be detached from garment 100, as shown in FIG. 2. Adjustable straps 22 are shown in further detail. The adjustable straps 22 may have a surface with a hook 45 closure portion and a loop closure portion, e.g., Velcro®, spaced from the hook portion one of the attachment straps 14, 16 may have a ring or slot through which one of the straps 22 may be fed, folded back onto itself, and secured by coupling the hook closure portion to the loop closure portion. It is understood that any known mechanism for securing 50 and adjusting an adjustable strap 22 is contemplated by the present invention.

FIG. 3 illustrates a top-down sectional view of the garment 100. FIG. 3 more clearly illustrates the belt 10 secured circumferentially around a user's 30 waist using the clasping mechanism 12. The pads 200 are shown removably affixed to the attachment straps 14, 16 using clips 24.

It should be understood, of course, that the foregoing relates to exemplary embodiments of the invention and that 60 modifications may be made without departing from the spirit and scope of the invention as set forth in the following claims.

What is claimed is:

1. A lower body garment comprising:
a belt with a buckle, wherein the belt is operative to suspend the lower body garment from a waist of a user;

foundation straps having longitudinally spaced apertures formed therein, a proximal end of each of the foundation straps being joined to said belt, wherein a first pair of the foundation straps are adapted to extend longitudinally along a first leg of the user with the first leg positioned between the first pair, a second pair of the foundation straps are adapted to extend longitudinally along a second leg of the user with the second leg positioned between the second pair, and wherein the longitudinally spaced apertures are configured to accommodate a set of complementary, correlating fasteners on the surface of a set of leg pads fasteners aligned along an axis perpendicular to the foundation straps;

at least one first adjustable strap adapted to extend across a rear of the first leg, thereby fastening the first pair to the first leg; and

at least one second adjustable strap adapted to extend across a rear of the second leg, thereby fastening the second pair to the second leg.

10

15

2. The lower body garment of claim 1, wherein the fasteners are clasps.

3. The lower body garment of claim 1, further comprising a first elastic strap and a second elastic strap, each configured to lie across a front portion of a thigh the user, the first elastic strap joined to the first pair, and the second elastic strap joined to the second pair.

4. The lower body garment of claim 1, wherein the at least one first adjustable strap has a first end joined to an outer strap of the first pair, extends through a loop joined to an inner strap of the first pair, and fastens to itself; and the at least one second adjustable strap has a first end joined to an outer strap of the second pair, extends through a loop joined to an inner strap of the second pair, and fastens to itself.

5. The lower body garment of claim 1, wherein the at least one first adjustable strap and the at least one second adjustable strap both include an ankle level strap, a knee level strap, and a thigh level strap.
